(57) **CLAIM**

The ornamental design for an industrial robot, as shown and described.

DESCRIPTION

FIG. 1 is a front, right perspective view of the industrial robot;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front, left perspective view thereof; and,

FIG. 9 is a cross-sectional view taken along 9-9 in FIG. 2. The evenly spaced broken lines depict parts of the industrial robot that form no part of the claimed design.

1 Claim, 9 Drawing Sheets
